(57) **CLAIM**

The ornamental design for a plank installation tool, as shown and described.

DESCRIPTION

FIG. 1 is a front perspective view of a plank installation tool, showing our new design;

FIG. 2 is a front perspective view thereof;

FIG. 3 is a rear perspective view thereof;

FIG. 4 is a front elevational view thereof;

FIG. 5 is a rear elevational view thereof;

FIG. 6 is a top plan view thereof, the bottom plan view being a mirror image thereof;

FIG. 7 is a left-side elevational view thereof; and,

FIG. 8 is a right-side elevational view thereof.

The broken lines illustrating planks in FIG. 1 depicts environmental matter that forms no part of the claimed design. The remaining broken lines in the figures depict portions of the plank installation tool that form no part of the claimed design.
